SYNCHRONIZING SYSTEM

Clyde Edwin Hallmark, Fort Wayne, Ind., assignor, by mesne assignments, to Farnsworth Research Corporation, a corporation of Indiana

Application February 1, 1946, Serial No. 644,872

11 Claims. (Cl. 250—36)

1

This invention relates to synchronizing systems, and particularly relates to a method of and system for synchronizing a low frequency wave generator and a high frequency wave generator.

The problem frequently arises of synchronizing two harmonically related wave generators. In the television art, for example, it is necessary for the proper reproduction of the television image to interlock with respect to time the field frequency wave of 60 cycles per second with a wave of 31,500 cycles per second, corresponding to twice the line frequency. Present television standards require the transmission of 60 fields per second and 525 lines per frame, each frame comprising two fields. Accordingly, the line frequency is 15,750 cycles per second. In television systems, synchronization is further complicated by the fact that a low frequency generator is usually coupled to the 60 cycle power line and, therefore, follows the variations in frequency of the power line.

A conventional synchronizing system suggested for this purpose employs frequency dividers for stepping down the frequency of the high frequency wave to that of the low frequency wave. The two waves of substantially equal frequency are then compared in phase to derive a signal which may be utilized for controlling one of the two wave generators. A system of this type suffers from the drawback that a chain of frequency dividers, such as multivibrators, is required for reducing the frequency of the high frequency wave to that of the low frequency wave. Another synchronizing system has been proposed where the low frequency and high frequency waves are compared directly. To this end, a pulse, which is narrow in comparison with a half cycle of the high frequency wave, is derived from the low frequency sinusoidal wave. The narrow pulse is superimposed on the high frequency sinusoidal wave and rectified to derive a control signal for controlling the frequency of the high frequency wave generator. This system has the drawback that extremely narrow pulses must be developed from a low frequency sinusoidal wave. These narrow pulses cannot be used for any other purpose, while the high frequency sinusoidal wave must then be shaped to derive high frequency pulses which are required for the synchronizing signal of a television system.

It is an object of the present invention, therefore, to provide a novel synchronizing system which will overcome the above mentioned drawbacks of prior systems and which will be comparatively simple in construction and reliable in operation.

A further object of the invention is to provide a method of and system for synchronizing a low frequency wave generator and a high frequency wave generator harmonically related thereto

2

where the low frequency pulses required for deriving a frequency control signal may have a time duration substantially equal to that of a full cycle of the high frequency waves.

5 In accordance with the present invention, there is provided a synchronizing system comprising means for developing low frequency pulses substantially at a frequency f and means for developing high frequency pulses substantially at a frequency nf , where n is an integer. Means are provided for selecting groups of the high frequency pulses at recurring time intervals equal to the reciprocal of the frequency f . Means are further provided for developing a pedestal wave having the same frequency as the low frequency pulses and means for mixing the selected groups of high frequency pulses with the pedestal wave. Thus a frequency control signal is derived. Finally means are provided for controlling the frequency of one of the pulses in accordance with the frequency control signal. In this manner the high frequency pulses are synchronized with the low frequency pulses.

For a better understanding of the invention, 25 together with other and further objects thereof, reference is made to the following description taken in connection with the accompanying drawings, and its scope will be pointed out in the appended claims.

30 In the accompanying drawings, Fig. 1 is a block diagram of a synchronizing system embodying the present invention, while Fig. 2 is a detailed circuit diagram of the synchronizing system of Fig. 1.

35 Referring now to Fig. 1, there is illustrated a synchronizing system comprising sinusoidal wave generator 1 which is arranged to develop a sinusoidal wave at the frequency f which may, for example, equal 60 cycles per second. Generator 40 1 is loosely coupled to lead 2 which may, for example, be a power line, from which a sinusoidal input wave of the frequency f may be obtained. Accordingly, generator 1 will follow the average or slow variations in frequency of the input wave obtained from lead 2. The sinusoidal wave developed by low frequency generator 1, as illustrated at 3, is passed through pulse shaper 4 where pulses 5 at the frequency f are developed. Pulses 5 preferably have a width of the order of 50 20 microseconds.

There is further provided a high frequency sinusoidal wave generator 6 which develops a sinusoidal wave indicated at 7 at the frequency nf , where n may, for example, be equal to 525 so that the frequency nf equals 31,500 cycles per second. High frequency sinusoidal wave 7 is passed through pulse shaper 8 to develop high frequency pulses at the frequency nf indicated at 10. High frequency pulses 10 preferably have 60 a width of the order of 5 microseconds.

In accordance with the present invention every n th pulse of high frequency pulses 10 is selected to derive pulses at the frequency f . This is accomplished by keyed amplifier 11 connected to the output of pulse shapers 4 and 8. Keyed amplifier 11 is arranged to be rendered operative whenever a low frequency pulse 5 is impressed thereon. During that time a high frequency pulse 10 is amplified. Thus keyed amplifier 11 is rendered operative at recurring time intervals 10 equal to the reciprocal of the frequency f which is $1/60$ second in the present example. Output wave 12 of keyed amplifier 11 accordingly consists of pulses having a time duration of approximately 5 microseconds and recurring at the frequency f . An output signal consisting of pulses at the frequency f may be derived from lead 13 connected to the output of keyed amplifier 11, while an output signal consisting of pulses recurring at the frequency nf may be obtained from lead 14 connected to the output of pulse shaper 8. The pulses obtained from output leads 13 and 14, therefore, have a time duration of approximately 5 microseconds. The pulses derived from output leads 13 and 14 may be utilized, for example, for developing synchronizing or blanking signals of the type required in a television system.

For the purpose of comparing the phases of the waves developed by generators 1 and 6, a wave having a sloping portion is derived from low frequency pulses 5 by means of saw-tooth wave shaper 15. Wave 16 developed by wave shaper 15 may be of triangular or saw-tooth shape, as illustrated, or it may have any wave form comprising a sloping portion such as a sinusoidal wave or a symmetrical saw-tooth wave. Saw-tooth wave 16 preferably has a time duration which equals that of low frequency pulses 5, that is, a time duration of approximately 20 microseconds.

By means of mixer 17 connected to the output of keyed amplifier 11 and of saw-tooth wave shaper 15, narrow pulses 12 are set on the sloping portion of saw-tooth wave 16 as illustrated at 18. Thus saw-tooth wave 16 serves as a pedestal for pulses 12. Depending on the phase relationship between pulses 12 derived from high frequency generator 6 and saw-tooth wave 16 derived from low frequency generator 1, the position of pulses 12 will vary with respect to saw-tooth wave 16. In other words, the height of pulses 12 will vary with respect to a reference potential depending upon the phase relationship between low frequency wave 3 and high frequency wave 7. However, the height of pulses 12 of wave 18 will only then be an indication of this phase relationship when pedestal wave 16 has a sloping portion. Wave 18 is rectified and may be amplified by rectifier and D. C. amplifier 20 to derive an amplified output signal which is representative of this phase relationship. The frequency control signal developed by D. C. amplifier 20 may be passed through low pass filter 21 where the alternating current components of the control signal are removed. The filtered frequency control signal may be used for controlling automatic frequency control circuit 22 which in turn controls the frequency of high frequency generator 6 in a conventional manner.

As stated previously, the time duration of low frequency pulses 5 as well as that of saw-tooth wave 16 may be between 20 to 30 microseconds, that is, of the order of one cycle of the high frequency wave. Since high frequency pulses 12

have a time duration of the order of 5 microseconds, the width of saw-tooth wave 16 is sufficient to serve as a pedestal for pulses 12 for purposes of phase comparison.

It is also feasible to select a plurality of pulses instead of one pulse each time keyed amplifier 11 is rendered operative by the arrival of a low frequency pulse 5. All that is necessary is to make low frequency pulses 5 slightly broader or of larger time duration so that keyed amplifier 11 is rendered operative for a length of time sufficient to pass a plurality of pulses instead of one. Saw-tooth wave 16 preferably should have substantially the same width as low frequency pulses 5. Accordingly a group of pulses might be set on the sloping portion of saw-tooth wave 16 instead of one pulse. However, the synchronizing system of the invention will be more sensitive to changes in phase when low frequency pulses 5 are sufficiently narrow to select one of high frequency pulses 10 rather than a plurality thereof every time keyed amplifier 11 is rendered operative.

Referring now to Fig. 2, there is illustrated the synchronizing system of Fig. 1 in greater detail. The circuit of Fig. 2 is separated by dotted lines into component parts which are designated by the same reference numerals as were used in Fig. 1 to facilitate identification of the circuit. Low frequency sinusoidal wave generator 1 is of the resistor capacitor or RC type. RC oscillator 1 comprises triode 25 having its grid coupled to the anode through delay network 26. Delay network 26 comprises three sections each including a series condenser 27 and a shunt resistor 28. Shunt resistor 30 arranged in series with resistor 31 is adjustable for manual control of the phase delay introduced by network 26. Triode 25 will oscillate at the frequency for which network 26 introduces a phase shift of 180 degrees. For the circuit constants of delay network 26 shown in Fig. 2, triode 25 will develop a sinusoidal wave at a frequency of 60 cycles.

The anode voltage may be supplied to the anode of triode 25 from voltage source 29 through low pass filter 32. Input lead 2, which may be connected to the power line, supplies a 60 cycle sinusoidal wave and is loosely coupled to the grid of triode 25 through coupling resistor 33. Thus RC oscillator 1 will follow slow variations in frequency of the input wave obtained from lead 2.

The sinusoidal output wave of oscillator 1 may be obtained from the plate of triode 25 which is coupled through coupling condenser 34 to the cathode of triode 35 arranged as a diode rectifier. The input signal is coupled across cathode resistor 36 of rectifier 35, and the rectified output signal is developed across anode resistor 37. The output signal of rectifier 35 consists of a rectified sinusoidal half-wave of negative polarity as indicated at 38. Sinusoidal half-wave 38 is cut off or clipped by clipper 40, the output signal developed across anode resistor 41 being shown at 42.

Square topped wave 42 is passed through differentiating network 43 which comprises a series condenser and a shunt resistor and is coupled to the grid of triode 44, negatively biased through potentiometer 45. The wave developed by differentiating network 43 is indicated at 46 and includes comparatively sharp peaks. Triode 44 is arranged as a clipper tube which clips off the sharp peaks of wave 46. The output signal of clipper 44 is developed across anode resistor 47

and indicated at 48. Wave 48 consists of pulses of negative polarity, each having a time duration of 300 microseconds. Output pulse 48 is again passed through a differentiating network 50 where the pulses are narrowed. Differentiating network 50 is connected to the grid of clipper tube 51. The grid of clipper tube 51 is negatively biased by potentiometer 52. Output pulse 53 developed across anode resistor 49 is similar in shape to output pulse 48 but has a width of 20 microseconds only.

Output pulse 53 is amplified by tube sections 54 and 55 arranged in a common envelope in the manner of a duplex tube. The anode of tube section 54 is coupled to the grid of tube section 55 arranged as a cathode follower. Amplified output signal 56 of positive polarity is developed across cathode resistor 57 of tube section 55. Output signal 56 has a time duration of 20 microseconds and consists of pulses of positive polarity having a peak-to-peak voltage of 160 volts and recurring at a frequency of 60 cycles per second.

High frequency sinusoidal wave generator 6 also is arranged as an oscillator of the RC type. RC oscillator 6 includes pentode 60 having its control grid coupled to the anode through delay network 61 comprising four sections, each consisting of a series condenser 62 and a shunt resistor 63. Resistor 64 is adjustable for manual control of the frequency of oscillator 6. Automatic frequency control tube 65 acts as a variable shunt resistor of one section of delay network 61. Delay network 61 is designed to introduce a 180 degree phase shift between the control grid and the anode of pentode 60 at a frequency of 31,500 cycles per second. By varying the resistance of automatic frequency control tube 65, the frequency developed by oscillator 6 may be varied. The plate voltage of pentode 60 is supplied through low pass filter 66. The suppressor grid of pentode 60 is connected to ground, as is conventional, while the screen grid is supplied with a suitable positive voltage through resistor 67.

The sinusoidal wave developed by high frequency generator 6 at the frequency of 31,500 cycles per second is derived from the plate of pentode 60 and is connected to pulse shaper 8 which has been shown in block form to avoid confusion. Pulse shaper 8 may be similar to pulse shaper 4 and should be arranged to develop output pulses at a frequency of 31,500 cycles per second, each pulse having a time duration of approximately 5 microseconds. Output pulses at a frequency of 31,500 cycles per second may be obtained from output lead 14 connected to the output of pulse shaper 8.

The output of pulse shaper 8 is also connected to the control grid of pentode 70 which is arranged as a keyed amplifier. The cathode and the suppressor grid of pentode 70 are both connected to ground. The screen grid of pentode 70 is connected to ground through resistor 71 so that it is normally at ground potential thus rendering pentode 70 inoperative. Output pulses 56 developed by pulse shaper 4 are supplied to the screen grid of pentode 70 through coupling condenser 72. Every time a pulse 56 of positive polarity is impressed upon the screen grid of pentode 70, its potential is sufficiently raised to render pentode 70 operative for the time duration of pulse 56. During that time a pulse or a plurality of pulses, as the case may be, developed by pulse shaper 8 is amplified by keyed amplifier 70. 75 a frequency control signal, and means for con-

The output signal is developed across anode resistor 73 and fed to mixer 17. An output signal consisting of pulses, each having a time duration of approximately 5 microseconds, and having a frequency of 60 cycles per second may be obtained through output lead 13.

Output pulses 56 developed by pulse shaper 4 are further shaped in saw-tooth wave shaper 15 to derive a saw-tooth wave. Shaper 15 comprises differentiating network 75 where pulses 56 are differentiated to develop a wave indicated at 76 which is clipped by clipper 77 having a suitable grid bias battery 78. The clipped wave which is of saw-tooth or triangular wave form as indicated at 80 is supplied to mixer 17 as is the output signal of keyed amplifier 70. Saw-tooth wave 80 has substantially the same width as pulses 56, that is, a time duration of approximately 20 microseconds. In mixer 17 the narrow 60 cycle pulses derived from keyed amplifier 70 are set on triangular wave 80 as shown at 18 in Fig. 1.

The output signal or mixer 17 is rectified and amplified by rectifier and D. C. amplifier 20 and passed through low pass filter 21 which is arranged to remove the alternating current component of the signal. The rectified and filtered frequency control signal is supplied to the control grid of automatic frequency control tube 65. Accordingly, a control signal of variable voltage depending upon the phase difference of the pulses developed by pulse shapers 4 and 8 is impressed upon the control grid of tube 65, thus varying its resistance. Automatic frequency control tube 65 acts as a variable resistor of one section of delay network 61 thereby to control the frequency of pentode oscillator 60 in accordance with the control signal.

While it will be understood that the circuit specifications of the synchronizing system of the invention may vary according to the design for any particular application, the values of the circuit constants of the synchronizing circuit of Fig. 2 are shown in the drawings, by way of example only, as suitable for developing pulses at frequencies of 60 cycles per second and of 31,500 cycles per second, respectively. The tubes shown in Fig. 2 preferably are of the following types:

40 Triodes 25, 35, 40, 44 and 51. 1/2 Type 6SL7-GT
45 Pentodes 60 and 70. Type 6AC7
50 Triode 65. 1/2 Type 6SN7-GT

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A synchronizing system comprising means for developing low frequency pulses substantially at a frequency f , means for developing high frequency pulses substantially at a frequency nf , where n is an integer, means rendered operative only by said low frequency pulses for selecting groups of said high frequency pulses at recurring time intervals equal to the reciprocal of said frequency f , means for shaping said low frequency pulses to develop a pedestal wave having the same frequency as said low frequency pulses, means for mixing said selected groups of high frequency pulses with said pedestal wave to derive 70 a frequency control signal, and means for con-

trolling the frequency of one of said pulses in accordance with said frequency control signal.

2. A synchronizing system comprising means for developing low frequency pulses substantially at a frequency f , means for developing high frequency pulses substantially at a frequency nf , where n is an integer, said low frequency pulses having each a duration of the order of the reciprocal of said high frequency, a keyed amplifier rendered operative only by said low frequency pulses for selecting groups of said high frequency pulses at recurring time intervals equal to the reciprocal of said frequency f , means for shaping said low frequency pulses to develop a wave having a sloping portion and having the same frequency and substantially the same duration as said low frequency pulses, means for superimposing said selected groups of high frequency pulses upon said sloping wave portions to derive a frequency control signal, and means for controlling the frequency of said high frequency pulses in accordance with said frequency control signal.

3. A synchronizing system comprising a first oscillator for developing a low frequency sinusoidal wave substantially at a frequency f , a power line for supplying a sinusoidal wave substantially at said frequency f , said power line being loosely coupled to said first oscillator, means for deriving low frequency pulses from said low frequency sinusoidal wave, said low frequency pulses having the same frequency as said low frequency wave, a second oscillator for developing a high frequency sinusoidal wave substantially at a frequency nf , where n is an integer, said low frequency pulses having each a duration of the order of the reciprocal of said high frequency, means for deriving high frequency pulses from said high frequency sinusoidal wave, said high frequency pulses having the same frequency as said high frequency wave, means controlled only by said low frequency pulses for selecting groups of said high frequency pulses at recurring time intervals equal to the reciprocal of said frequency f , means for shaping said low frequency pulses to derive a wave having a sloping portion and substantially the same duration as that of said low frequency pulses, means for superimposing said selected groups of high frequency pulses upon said sloping wave portions to derive a frequency control signal, and means for controlling said second oscillator in accordance with said frequency control signal.

4. A synchronizing system comprising means for developing low frequency pulses substantially at a frequency f , means for developing high frequency pulses substantially at a frequency nf , where n is an integer, said low frequency pulses having each a duration of the order of the reciprocal of said high frequency, means rendered operative only by said low frequency pulses for selecting every n th of said high frequency pulses, means for shaping said low frequency pulses to develop a wave having a sloping portion and having the same frequency and substantially the same duration as said low frequency pulses, means for mixing said selected high frequency pulses with said sloping wave to derive a frequency control signal, and means for controlling the frequency of one of said pulses in accordance with said frequency control signal.

5. A synchronizing system comprising means for developing low frequency pulses substantially at a frequency f , means for developing high frequency pulses substantially at a frequency nf ,

where n is an integer, said low frequency pulses having each a time duration of more than

$$\frac{1}{2nf} \text{ and less than } \frac{1}{nf}$$

5 a keyed amplifier controlled by said low frequency pulses for selecting every n th of said high frequency pulses, means for shaping said low frequency pulses to derive a wave having a sloping portion and substantially the same duration as that of said low frequency pulses, means for superimposing said selected high frequency pulses upon said sloping wave portions to derive a composite wave, means for rectifying and filtering said composite wave to derive a frequency control signal, and means for controlling the frequency of one of said pulses in accordance with said frequency control signal.

6. A synchronizing system comprising means for developing a low frequency sinusoidal wave substantially at a frequency f , means for deriving low frequency pulses from said low frequency sinusoidal wave, said low frequency pulses having the same frequency as said low frequency wave, 20 means for developing a high frequency sinusoidal wave substantially at a frequency nf , where n is an integer, means for deriving high frequency pulses from said high frequency sinusoidal wave, said high frequency pulses having the same frequency as said high frequency wave, said low frequency pulses having each a time duration of the order of one cycle of said high frequency sinusoidal wave, a keyed amplifier rendered operative by said low frequency pulses for selecting every n th of said high frequency pulses, means for shaping said low frequency pulses to derive a wave having a sloping portion and substantially the same duration as that of said low frequency pulses, means for setting said selected high frequency pulses upon said sloping wave portions to derive a frequency control signal, and means for controlling the frequency of one of said sinusoidal waves in accordance with said frequency control signal.

45 7. A synchronizing system comprising a low frequency oscillator for developing a low frequency sinusoidal wave substantially at a frequency f , a power line for supplying a sinusoidal wave substantially at said frequency f , said power line being loosely coupled to said low frequency oscillator, means for deriving low frequency pulses from said low frequency sinusoidal wave, said low frequency pulses having the same frequency as said low frequency wave, a high frequency oscillator for developing a high frequency sinusoidal wave substantially at a frequency nf , where n is an integer, means for deriving high frequency pulses from said high frequency sinusoidal wave, said high frequency pulses having the same frequency as said high frequency wave, said low frequency pulses having each a duration of the order of the reciprocal of said high frequency, means controlled by said low frequency wave for selecting every n th of said high frequency pulses, means for shaping said low frequency pulses to derive a wave having a sloping portion and substantially the same duration as that of said low frequency pulses, means for superimposing said selected high frequency pulses upon said sloping wave portions to derive a frequency control signal, and means for controlling said high frequency oscillator in accordance with said frequency control signal.

70 8. The method of synchronizing two harmonically related waves which comprises develop-

ing low frequency pulses substantially at a frequency f , developing high frequency pulses substantially at a frequency nf , where n is an integer, selecting groups of high frequency pulses at recurring time intervals equal to the reciprocal of said frequency f , shaping said low frequency pulses to develop a pedestal wave having sloping portions of the same frequency as said low frequency pulses, said sloping wave portions having each a duration of the order of the reciprocal of said high frequency, mixing said selected groups of high frequency pulses with said pedestal wave to derive a frequency control signal, and controlling the frequency of one of said pulses in accordance with said frequency control signal.

9. The method of synchronizing two harmonically related waves which comprises developing a low frequency sinusoidal wave substantially at a frequency f , developing a high frequency sinusoidal wave substantially at a frequency nf , where n is an integer, deriving high frequency pulses from said high frequency sinusoidal wave, said high frequency pulses having the same frequency as said high frequency wave, selecting groups of said high frequency pulses at recurring time intervals equal to the reciprocal of said frequency f , developing a wave having sloping portions and having the same frequency as said low frequency sinusoidal wave, said sloping wave portions having each a duration of the order of the reciprocal of said high frequency, setting said selected groups of high frequency pulses upon said sloping wave portions to derive a frequency control signal, and controlling the frequency of one of said sinusoidal waves in accordance with said frequency control signal.

10. The method of synchronizing two harmonically related waves which comprises developing low frequency pulses substantially at a frequency f , developing high frequency pulses substantially at a frequency nf , where n is an integer, said low frequency pulses having each a duration of the order of the reciprocal of said high frequency, selecting every n th of said high frequency pulses, developing a wave having a sloping portion and having the same frequency and substantially the same duration as said low frequency pulses, superimposing said selected high frequency pulses upon said sloping wave portions to derive a frequency control signal, and controlling the frequency of one of said pulses in accordance with said frequency control signal.

quency pulses, superimposing said selected high frequency pulses upon said sloping wave portions to derive a frequency control signal, and controlling the frequency of one of said pulses in accordance with said frequency control signal.

11. The method of synchronizing two harmonically related waves which comprises developing a low frequency sinusoidal wave substantially at a frequency f , deriving low frequency pulses from said low frequency sinusoidal wave, said low frequency pulses having the same frequency as said low frequency wave, developing a high frequency sinusoidal wave substantially at a frequency nf , where n is an integer, deriving high frequency pulses from said high frequency sinusoidal wave, said high frequency pulses having the same frequency as said high frequency wave, said low frequency pulses having each a duration of the order of the reciprocal of said high frequency, selecting every n th of said high frequency pulses, shaping said low frequency pulses to derive a wave having a sloping portion and substantially the same duration as said low frequency pulses, superimposing said selected high frequency pulses upon said sloping wave portions to derive a frequency control signal, and controlling the frequency of said high frequency sinusoidal wave in accordance with said frequency control signal.
